**CONTINUOUS CHAIN PRESS FOR THE
WOOD INDUSTRY**

Walter Köhler, Gutersloh, and Willi Riesmeier, Lubbecke,
Westphalia, Germany, assignors to Firma Ima-Kless-
mann K.G., a corporation

Filed Mar. 30, 1964, Ser. No. 355,744
10 Claims. (Cl. 144—281)

The present invention relates to the field of steam heated continuously operating chain presses for the wood industry as are used e.g. for the processing of boards, sheets, etc. into veneers, cementing or similar. Such continuously operating presses are known as such, are, however, used only in minor degrees, because for the steps to be performed thereby, there must generally be applied in addition to pressure also heat. Particularly for cementing work there must be used comparatively high temperatures of 200° to 300° C. in order that the cement used does rapidly and thoroughly set, because with such presses there are to be achieved operational speeds as high as possible. The intended operational speeds are in the range of up to 20 m./min.

The expert is familiar with the fact that when cementing wood plates, e.g. when glueing veneers onto plates, there must be applied a certain amount of heat and the higher the temperature within the continuous press, the shorter e.g. can be the continuous press in order to apply during a desired higher operational speed the required amount of heat. The structural length of the continuous press depends of course also on other parameters, like e.g. among others the operational speed. The stationary steam heating of these known continuous chain presses acts indirectly by heat radiation onto the chain members and in consequence only incompletely. This is the reason why in already existing continuous presses the individual chain members are supplied with heat by means of electric energy, it was, however, soon found that these types of presses when heated electrically do require extremely high current densities, and such high current densities can be used in practice only with relatively high difficulties, and respectively are extremely uneconomical.

The present invention is based on the object to propose for a continuously operating chain press a direct heating, in order to effect the heating of such a chain press with a comparatively inexpensive medium in a particularly economical manner in this specific art.

According to the invention a continuously operating chain press for the wood industry for the processing of plates is characterized in that the individual chain members are provided for a direct steam heating with steam conduits and are interconnected and at least one member of each chain is provided with a steam admission and discharge conduit, each of which is connected with a frame stationary steam connecting line through a connecting conduit member performing only a reciprocating movement and permitting a rotational movement. This connecting conduit member is passed in the center between and in both directions moving chain stringer on a guiding track extending between the shaft of the front and rear reversal roller. The connecting conduit member comprises a double stuffing box for the admission and discharge conduits which are rotatably connected with these at the chain members and mounted centrally in respect to each other. The connecting conduit member is connected through tubes or telescopic pipes with the frame stationary steam connecting conduit. The connecting conduit member is preferably arranged within the endless chains passed over lateral reversal rollers without continuous shafts, with guiding track and tubes for telescopic pipes. Suitably there is arranged adjacent to the guiding track of the stuffing box a pair of reversal

2

rollers in a second parallel guiding track for the tubes and an oppositely operating rope connection. The chain members are interconnected by means of flexible tubes for carrying the steam and preferably there are provided two steam circuits in the chains, i.e. all even numbered members are interconnected and all odd numbered members are interconnected, so that the connecting tubes between the members, under passing one member each, are sufficiently long to accommodate a respective bending when a reversal of the chain is effected.

The present invention is in consequence based on the recognition that it is possible to directly heat the members of an endless rotating chain with steam if the admission and discharging conduit for the steam connected at one or several points of the chain is passed to a connecting conduit member which translates the rotating movement of the connecting chain member into a reciprocating and straight line movement and permits a rotating movement of the admission conduit, so that between the connecting conduit member and the stationary connecting point there is to be equalized only a reciprocating movement. A continuous chain press according to the invention will be explained by means of an embodiment with reference to the enclosed drawings. In the drawings:

FIGURE 1 is a schematic vertical section through a continuous chain press with upper and lower endless chain according to the invention,

FIGURE 2 is a horizontal longitudinal section corresponding to FIGURE 1,

FIGURE 3 is a section through the connecting conduit member with admission and discharge conduit for the steam in a chain member,

FIGURE 4 is a section through a chain section,

FIGURE 5 is a plan view from below onto the individual chain members.

The continuous chain press comprises a support with two frames of which the lateral sides 1 respectively 2 for the upper chain resp. lower chain 6 are shown in FIGURE 1. In FIGURE 2 these lateral sides for the upper chain are shown in section. The frames in which the chains 6 are supported and guided are movable in respect to each other, and preferably one of the two frames, i.e. the lower frame, is stationarily mounted in the machine support, while the upper frame can be lifted and lowered in order to effect the desired compressive force. In the lateral sides 1 and 2 there are rotatably supported the shafts 5 of the front reversal rollers 3 and the rear reversal rollers 4. These shafts 5 are in the form of stub shafts and thus these are not continuous between the reversal rollers 3 and 4 arranged within the side walls 1 resp. 2. The space within the chains 6 is in consequence free of all obstructions. The individual chain members 7 are guided (not shown) at their narrow sides in guides with roller supports at the interior sides of the side walls 1 and 2 and are reinforced against bending at their central part with herewith connected girders 8.

About from the connecting line of the stub shaft of the front reversal rollers 3 to the connecting line of the stub shafts of the rear reversal rollers 4 there is mounted in the space surrounded by the upper and lower stringer of each rotating endless chain, a straight guiding track 9 comprising an upper track bar 10 and a lower track bar 11. These track bars 10 and 11 are e.g. of a square cross-section and are stationarily supported in the same distance in respect to each other and from the center line between the upper and the lower stringer of the chain in such a manner, that with one edge these are adjacent to each other. These track bars 10 and 11 serve for the guiding of a connecting conduit member 12 for the steam supply and discharge connecting line from the chain to a stationary means.

The connecting conduit member 12 substantially comprises a double stuffing box shiftable with upper and lower pairs of guiding rollers 13. The rollers of each pair turn about axes forming an angle between them, preferably of 90°, so that the rollers engage adjacent sides, respectively, of the square cross-section track bars 10 and 11 between the two shafts 5 of the chain.

At least one section 14 of each chain has tube connections 15, 16 connected with a double pipe 17. This double pipe carries one conduit 19 within the other conduit 20, so that at its end adjacent to and directed toward the chain member there are provided two side-by-side pipe connections and at its other end, opening at an angle to such pipe connections because of the elbow 18, there are two concentrically arranged pipe ends. One of these two pipe ends, preferably the interior pipe end 19, is the supply pipe for the steam and the encircling pipe 20 is the discharge pipe for the steam.

The discharge pipe 20 for the steam in the front part of the stuffing box is sealingly and rotatably supported in a connecting housing 25 reciprocable in opposite directions along track 9 in synchronism with corresponding movements of the connections 15, 16 between the conduits 19 and 20 and the chain 14 with packing 21 backed by a packing ring 22 and a compression flange nut 23. From one front area 24 there pass openings or a perforation into an annular chamber within the housing 25 connected with a port 26 through the housing wall of the stuffing box with a further (not shown in FIGURE 3) discharge pipe.

The interior steam supply pipe 19 is passed within the steam discharge pipe of substantially greater cross-section and has a flanged nipple 27 arranged in a further stuffing box with packing 28, which is pressed from the side of the stuffing box opposite the nipple flange by a screw lid and a helical spring 30 against a flange 31 projecting inward from the housing 25. The nipple 27 of the steam supply pipe 19 is mounted rotatably in the stuffing box packing 28, and the steam passes from the steam supply pipe (not shown in FIGURE 3) through a part 33 in the housing wall of the stuffing box 12 into a chamber 32 and from there through the nipple 27 into the supply pipe 19.

In view of the above explained structure of the stuffing box 12 the steam supply and steam discharge pipes 20 and 20 centrally arranged in this stuffing box are rotatable in respect to this stuffing box, so that these follow a rotation of the chain member 14 and on the other hand the stuffing box with its guiding rollers 13 follows on the tracks 10 and 11 in guided manner to the straight line movement of the chain member 14 in that it is carried along by the double pipe 17.

The steam supply and discharge ports 33 and 26 are guided by the stuffing box 12 through flexible tubes or hoses 34 to a stationary connection 35 in one of the side walls 1 of the press. These flexible tubes or hoses 34 only have to follow the reciprocating movement of the stuffing box 12 and are subjected only to slight bending forces. In order to achieve an unambiguous and clear position of the supply and discharge hose tube 34 in each position of the stuffing boxes at their guiding track 9, there is provided a guideway 36 for the hoses 34 parallel to the guiding track 9. This guideway guides a roller pair 37/38 which turn on axles slideable along upper tracks 39 and lower tracks 40 of the guideway 36. The rollers 37 and 38 are rigidly connected in order to maintain a uniform spacing. One roller 37 is engaged by the pair of hoses 34, while a pair of ropes 41 pass over the other roller 38, which ropes are secured to anchors 42 on the side wall 1 adjacent to the steam hose connections 35.

The roller pair 37/38 can be under spring action, the spring means being provided in the form of a tension spring not shown here, acting parallel to the guideway 36 for the rollers, i.e. preferably in the direction of the arrow 43. In view of the above explanations it will be

understood that by the rollers 37 and 38 and the pair of ropes 41, the hoses 34 are constantly maintained under tension between the stuffing box 12 and the hose connections 35 in all positions of movement of the stuffing box 12. In FIGURE 2 there is shown in full lines one terminal position of the stuffing box 12 with the chain member connected to it and the corresponding position of the guiding roller pair 37/38, and the other terminal position of such ports is shown in dashed lines.

In order to connect the steam heated chain members in such a manner that there is obtained a continuous steam circuit, the chain members 7 are interconnected by means of flexible tubes 47 as is shown in the FIGURES 4 and 5. Since in a connection of the directly adjacent chain members by means of flexible tubes the free tube length would not be sufficient for the accommodation of a sufficient bending, the steam circuit is subdivided by the chain members into two circuits, and in each case the even numbered chain members and the odd numbered chain members are interconnected through longer tube pieces, so that each tube piece is of sufficient length in order to be also passed around reversal rollers of smaller diameter and can accommodate the thereby occurring bending.

Each chain member is provided with two connecting members 44 and 45, each of which is angularly bent at its interior end 46. At these angular bent members 46, which pass at one chain member in the opposite direction, there are secured the flexible connecting tubes 47 and are passed to the points 46 of the steam admission respectively discharge conduit of the next but one chain member. Thus the tubes are of a sufficient length in order to permit a sufficient bending in the reversal rollers of the chain. The tubes 47 are arranged in three lines adjacent to each other so that the connection with the individual chain members does not result in substantial difficulties and in particular the heating channels within the chain members need not be guided in different manner.

What we claim is:

1. A fluid-heated endless press for pressing wood sheets and the like comprising hollow endless pressing means adapted to receive heating fluid therein, means guiding said pressing means for lengthwise movement in an elongated orbit, heating fluid supply conduit means having a connection to said pressing means, and guide means guiding portions of said heating fluid supply conduit means for reciprocation within the elongated orbit traversed by said endless pressing means as said connection to said pressing means moves orbitally.

2. A steam-heated endless chain press for pressing wood sheets and the like comprising a frame, a hollow endless chain adapted to receive steam therein for heating it, guide means supporting said chain from said frame and guiding said chain for lengthwise movement in an elongated orbit, steam supply and discharge conduit means connected between said frame and said endless chain, and conduit guide means guiding portions of said steam supply and discharge conduit means between their ends for reciprocation within the orbit of said endless chain in synchronism with orbital movement of the connections between said steam supply and discharge conduit means and said endless chain.

3. The chain press defined in claim 2, in which the endless chain orbit includes two opposite straight stretches, the conduit guide means includes a track located midway between such opposite straight stretches of the endless chain and conduit-engaging means guided by said track for reciprocation along it in opposite directions corresponding to the direction in which the connections between the steam supply and discharge conduit means and the endless chain move.

4. The chain press defined in claim 3, in which the steam supply and discharge conduit means between the conduit guiding means and the endless chain have a double elbow in which two conduit portions are disposed con-

centrically adjacent to the conduit guiding means, and a double stuffing box sealing between such concentric conduit portions, respectively, and said conduit guiding means.

5. The chain press defined in claim 3, in which the conduit guiding means includes a connecting housing to which the steam supply and discharge conduits are connected, said housing being reciprocable along the track.

6. The chain press defined in claim 5, in which the steam supply and discharge conduits include telescoping pipes connected to the frame.

7. The chain press defined in claim 2, in which the chain guide means includes at opposite ends of the chain orbit chain-supporting rollers spaced apart transversely of the direction of movement of the chain, and stub axles supporting the rollers from the frame so as to leave a space within opposite ends of the chain orbit and between the spaced-apart chain-supporting rollers, which space is unobstructed by chain-supporting structure.

8. The chain press defined in claim 3, and a second conduit guiding track generally parallel to the first conduit guiding track, and a roller mounted for reciprocation along said second guiding track and engageable by the

steam supply and discharge conduits for guiding the portions of the steam supply and discharge conduits between the frame and the first guide track.

9. The chain press defined in claim 2, in which the endless chain includes a series of hollow sections, and connecting conduit means interconnecting said hollow sections for transmitting steam therebetween.

10. The chain press defined in claim 9, in which the connecting conduit means connect each chain section to another chain section spaced apart to accommodate at least one chain section therebetween.
